Fig. 5

Fig. 6

FIG. 1 is a front elevational view of a handle attachment for door knob, showing my new design;

FIG. 2 is a side elevational view, the opposite side being substantially similar in appearance;

FIG. 3 is an elevational view of one end;

FIG. 4 is an elevational view of the opposite end;

FIG. 5 is a rear elevational view; and,

FIG. 6 is a median, longitudinal, sectional view, the plane of the section being indicated by the line 6-6 in FIG. 5.

The interrupted lines represent the outline of a typical door knob to which the handle is attached and are included to illustrate the environment in which the handle is used.

I claim:

The ornamental design for a handle attachment for door knob, as shown and described.
